Specification for Design.

Patented Sept. 22, 1914.

Application filed July 27, 1914. Serial No. 853,481. Term of patent 14 years.

To all whom it may concern:

Be it known that I, FREDRICK F. SCHOTTKY, a citizen of the United States, residing at New York, in the county of New York and State of New York, have invented a new, original, and ornamental Design for a Casing for Electric Gage-Lamps, of which the following is a specification, reference being had to the accompanying drawings, forming a part thereof.

Referring to the annexed sheet of drawings, Figure 1 represents a view in front elevation of my design for casing for elec-

tric gage lamps, and Fig. 2 is a side view thereof.

I claim—

The ornamental design for casing for electric gage lamps as shown.

In witness whereof I have hereunto set my hand in the presence of two subscribing witnesses.

FREDRICK F. SCHOTTKY.
